UNITED STATES PATENT OFFICE.

DON F. MANNING, OF VALLEY HEAD, ALABAMA.

WEDGE.

1,261,834.

Specification of Letters Patent. Patented Apr. 9, 1918.

Application filed April 12, 1917. Serial No. 161,635.

To all whom it may concern:

Be it known that I, DON F. MANNING, a citizen of the United States, residing at Valley Head, in the county of Dekalb, State of Alabama, have invented a new and useful Wedge; and I do hereby declare the following to be a full, clear, and exact description of the invention, such as will enable others skilled in the art to which it appertains to make and use the same.

The invention relates to wedges, being particularly a wedge designed for the use of lumbermen for felling and splitting lumber.

One of the objects of the invention is to provide a simple, inexpensive and durable device of this character capable of being easily driven in timber without the liability of the wedge changing its course when being struck by an ax or maul.

20 A further object is to provide a wedge which will prevent the two halves of a log being sawed from twisting or turning with respect to each other.

25 A still further object is to provide a wedge having ribs centrally disposed on its side faces and running longitudinally along the faces, the ribs being sharpened to a knife edge to allow them to cut their way in.

30 A still further object is to provide a wedge with centrally disposed longitudinal ribs on its side faces and to provide teeth on the edges of the ribs.

Other objects will appear in the detailed description which follows.

35 The actual reduction to practice may disclose certain advantages which can be derived by deviation from the structure shown in the drawings, and the right is claimed to deviate from these structures to any extent 40 compatible with the spirit of the appended claim.

The same numerals of reference designate the same parts in all of the figures of the drawings, wherein:

45 Figure 1 is an edge elevation of the improved wedge, constructed in accordance with the invention.

Fig. 2 is a perspective view of the wedge.

Fig. 3 is a side elevation of the wedge.

50 Fig. 4 is a section on the line 4—4 of Fig. 2.

In the drawing 1 represents a wedge which may be formed of any suitable material and is provided with a flat head 2 whose corners are rounded, as indicated at 3, to prevent the head from expanding or having 55 its corners or edges broken off when struck by an ax or maul.

The wedge 1 is provided with the ribs 7, which are serrated, leaving the teeth 8 with upper faces 9 substantially perpendicular 60 with a line projected through the center of the wedge. The bottom faces 10 of the teeth 8 are inclined toward the side faces of the wedge but at a more acute angle from the horizontal than the side faces of the wedge 65 incline. The advantage of serrating the ribs is apparent. When the wedge has been driven into a cut, the serrations preclude its backing out and it may always be driven forward to maintain firm contact with both 70 sides of the cut because of the shape of the serration. The ribs 7 themselves are designed to be removable from the wedge 1, being affixed to the wedge by insertion in the tapering dovetail slots formed in the 75 raised portion 11 on the side faces of the wedge.

It will be seen that the tapering shape of the slots in the raised portions 11 tends to tighten the rib 7 in the slots when the wedge 80 is being driven in a cut.

The invention having been described, what is claimed as new and useful is:

A wedge comprising a wedge shape body, each face of said body having an elongated 85 V-shaped dovetailed channel tapered upwardly, a removable rib V-shaped in cross section dovetailed upwardly and longitudinally into said channel and being tapered upwardly to correspondingly fit the channel, 90 the outer edge of said rib having upwardly and outwardly inclined ratchet teeth, as set forth.

In testimony whereof I have signed my name to this specification in the presence of 95 two subscribing witnesses.

DON MANNING.

Witnesses:

C. Y. CULBERSON,

B. R. THORNBURY.
